UNITED STATES PATENT OFFICE.

LOUIS KOCHER, OF OMAHA, NEBRASKA.

WINDOW SHUTTER.

Application filed April 23, 1923. Serial No. 633,999.

The invention relates to window shutters and has for its object to provide a device of this character formed from a plurality of slats adapted to be rolled upon a roller within the upper end of a window frame for storage purposes. The shutter is preferably disposed outside the window to protect the window from damage, incident to storms and also to exclude cold and heat.

10 A further object is to slidably mount the sides of the slat shutter in fixed upper channels on the inner faces of the sides of the window frame, and to hingedly connect lower channel sections to the first mentioned 15 channels, thereby allowing the lower portion of the shutter to be moved outwardly for allowing free circulation of air through the lower part of the window.

10 A further object is to provide the slats 20 forming the upper portion of the shutter with flexible connections, whereby the upper portion of the shutter will roll on the roller, and the lower portion of the shutter with connections between the slats, which connections are constructed in such a manner 25 whereby air may pass between the slats, or the slats may be moved into engagement with each other for excluding air.

10 A further object is to provide cable means 30 whereby the roller may be rotated from within the building.

With the above and other objects in view the invention resides in the combination and arrangement of parts as hereinafter set forth 35 shown in the drawings, described and claimed, it being understood that changes in the precise embodiment of the invention may be made within the scope of what is claimed without departing from the spirit 40 of the invention.

In the drawings:—

Figure 1 is a front elevation of a window frame, showing the shutter applied thereto.

Figure 2 is a vertical transverse sectional view through the window frame and the shutter, taken on line 2—2 of Figure 1.

Figure 3 is a detail perspective view showing adjacent slats in section and the loose connection therebetween.

50 Figure 4 is a detail perspective view of a portion of one of the guide channels showing the hinged connection therein.

Figure 5 is a horizontal sectional view through the lower portion of the window frame and shutter.

Referring to the drawings, the numeral 1 designates a conventional form of window frame, and 2 the slat shutter carried thereby at the outer side of the window sash 3. It has been found that the glasses 4 within the sash are often damaged in storms, particularly hail storms and to obviate this difficulty, as well as regulate the amount of air passing through the window, the slat shutter is primarily designed. Shutters as at present used are usually of the hinged type, which are hard to manipulate, particularly to close in a heavy wind. However by providing the slat shutter 2, which is vertically movable and guidable in vertically disposed channels 5 fixedly carried by the inner side of the frame 1, the shutter may be easily raised and lowered, even in an extremely heavy wind. The shutter 2 has its slats 7, which form its upper portion substantially in engagement with each other and connected together by flexible bands 8, which bands extend upwardly, and onto the roller 9 disposed in the upper portion of the window frame 1. It will be seen that when the roller 9 is rotated in the direction of the arrow a, the upper portion of the shutter will be rolled onto the roller, and will be out of sight. However when the upper portion of the shutter is wound around the roller 9, the lower portion of the shutter, which is formed from the spaced slats 10 will be raised to a position adjacent the upper sash 3, thereby allowing air to pass through the window frame when the lower sash is 90 raised. However the slats 10 are loosely connected together by means of a plurality of links 11, which links have slot connections 12 with transversely disposed pins 13, which extend through the slats, therefore it 95 will be seen that when the slats are suspended spaces will be formed between the slats incident to the weight thereof thereby allowing a limited amount of air to pass through the lower portion of the shutter for ventilating purposes. However, when the shutter is lowered to a position where the slats 10 will rest against each other, it will be seen that the spaces 14 between the slats will be closed, consequently light, heat or air will be excluded from passing through the window frame. The links 11 are formed from metal and extend into enlarged slots 15 in the slats 10, therefore it will be seen that the slats 100 may have a freedom of movement longitudi-

105

110

dinarily as the shutter moves upwardly and downwardly in the channels 5, thereby preventing sticking or jamming of the slats.

The lower sections 5^a of the channels 5 are hingedly connected at 16 to the upper sections 5, therefore it will be seen that the lower portion of the shutter may be forced outwardly at an angle, thereby allowing a relatively free passage of air through the lower portion of the window frame. To hold the lower portion of the shutter outwardly, pivoted bars 17 are provided, which bars are pivotally connected at 18 to the portions 5^a of the channels, and are provided with right angled portions 19 adapted to be received in sockets 20 for holding the lower portion of the shutter in outer position.

To raise and lower the shutter, an endless cable 21 is provided, which cable has its portion 22 disposed to the inside of the window frame where it can be easily reached and manipulated by a person within the building. Cable 21 extends upwardly over the pulley 23, thence through the side of the window frame and upwardly over the pulley 24 carried by the roller 9. Cable 21 after passing over the pulley 24 extends downwardly through the side of the window frame and under the pulley 25, therefore it will be seen that only the portion of the cable which is grasped by the operator during the manipulation of the device is exposed to view within the room.

From the above it will be seen that a window shutter is provided, which is formed from a plurality of slats and consequently the window shutter may be easily rolled onto a roller concealed within the upper portion of the window frame. It will also be seen that the amount of heat, light or air passing through the lower portion of the window may be regulated as desired, and that the shutter can be easily raised or lowered even in an extremely heavy wind.

The invention having been set forth what is claimed as new and useful is:—

A slat window shutter comprising an upper section, a lower section, said upper section and lower section being slidably mounted in guides formed from channel members, said lower section having its slats linked together and maintained in the same plane, said guides having their lower ends hingedly mounted and movable to angular positions with the guides, said upper sections being normally disposed in the upper portions of the guides, flexible connections between the slats of the upper section and the upper end of the lower section, a roller above the guides, said upper section being rollable onto the roller and limited in its upward movement by the upper end of the lower section.

In testimony whereof I hereunto affix my signature.

LOUIS KOCHER.
